UNITED STATES PATENT OFFICE.

RUDOLPH J. PICK, JR., OF CHICAGO, ILLINOIS.

AEROPLANE BRAKE.

Application filed May 26, 1925. Serial No. 32,598.

To all whom it may concern:

Be it known that I, RUDOLPH J. PICK, Jr., a citizen of the United States, residing at Chicago, in the county of Cook and State of Illinois, have invented certain new and useful Improvements in an Aeroplane Brake, of which the following is a specification.

This invention relates to improvements in aeroplanes, and is more particularly adapted to a brake mechanism therefor to facilitate the stopping of an aeroplane after the same has descended and has alighted on the landing surface.

A further object of the invention is to provide an aeroplane brake of the above mentioned character which includes a pair of drag fins or planes which are pivotally supported at their rear ends on the opposite sides of the fuselage of the aeroplane, means being provided for normally holding the fins or planes in an inoperative position, said fins being adapted to be automatically swung laterally with respect to the fuselage whereby the forward movement of the aeroplane after the same has landed will be retarded.

A still further object is to provide an aeroplane brake of the above mentioned character, which includes a means for releasing the latch mechanism associated with the fins, said release means being disposed with in easy access of the pilot of the aeroplane.

A still further object is to provide an aeroplane brake of the above mentioned character which will at all times be positive and efficient in its operation, the same being further simple in construction, inexpensive, strong and durable, and further well adapted to the purposes for which it is designed.

Other objects and advantages of this invention will become apparent during the course of the following description.

In the accompanying drawing forming a part of this application and in which like numerals designate like parts throughout the same:

Figure 1 is a fragmentary side elevation of the fuselage of an aeroplane showing my improved brake mechanism associated therewith, and the same being in its normally inoperative position, and

Figure 2 is a top plan view showing the brake mechanism in an operative position.

In the drawing, wherein for the purpose of illustration is shown the preferred embodiment of my invention, the numeral 1

designates a portion of the fuselage of an aeroplane, the cock pit being illustrated generally at 2. The sides of the fuselage are provided with substantially rectangular cut out portions, the same being preferably formed in the tail portion of the fuselage. Arranged in the cut-out portion are the drag fins or planes 3 and 4 respectively. Both of the drag fins or planes are hinged at their rear ends to the body or fuselage of the aeroplane as illustrated at 5. A latch receiving keeper 6 is provided on the inner side of each of the drag fins or plane adjacent the forward free end of each of the fins or planes, and the purpose thereof will hereinafter be more fully described. The latch mechanism which is provided for normally holding the drag fins or planes in a closed or inoperative position comprises a curved spring wire 7 which encircles the forward portion of the cock pit 2. The free ends 8 of the curved spring wire 7 are disposed through suitable guides 9 which are arranged at opposite sides of the cock pit and the free ends 8 are adapted to be received in the respective keepers 6 as is illustrated more clearly in Figure 1.

For the purposes of limiting the outward swinging movement of the drag fins or planes, I provide a stationary eye member 10, which is supported in the fuselage 1 forwardly of the rear ends of the fins or planes. The free end of the drag fin or plane 3 is connected to the stationary eye member 10 through the medium of the cables 11 and 12, and a similar pair of cables 13 and 14 respectively affords a connection between the outer end of the opposite drag fin or plane with the stationary eye member 10.

Normally, the drag fins or planes are maintained in a closed or inoperative position, so that the outer faces of the fins or planes will lie flush with the outer faces of the sides of the fuselage, and the latch mechanism will maintain the drag fins in an inoperative or closed position, so that the aeroplane may be used in the usual manner, and the drag fins or planes will not in any way retard the forward movement of the aeroplane while in flight.

As an aeroplane having my improved brake mechanism associated therewith descends, and alights on the landing surface, the pilot exerts a forward movement on the curved spring wire 7 causing the free end 8 thereof to become disengaged from the

- keepers 6, and the drag fins or planes will then automatically swing laterally to an operative position as is shown in Figure 2 of the drawing so as to be disposed at substantially right angles to the fuselage, the cables limiting the outward swinging movement of the drag fins or planes so as to prevent the drag fins from swinging rearwardly against the sides of the tail of the fuselage.
- 10 When the drag fins or planes are in the position as shown in Figure 2 of the drawings, the same will act as an arrestor and retard the forward movement of the aeroplane along the landing surface, thereby causing the aeroplane to stop in a short distance.
- It will thus be seen from the foregoing description, that an aeroplane brake has been provided which may be readily and easily installed on an aeroplane without necessitating any material alterations, and the simplicity of the device renders the same positive and efficient in its operation at all times.
- While I have shown the preferred embodiment of my invention it is to be understood that minor changes coming within the scope of the invention may be resorted to without departing from the spirit of the invention and the scope of the appended claims.
- 30 Having thus described the invention, what I claim as new and desire to secure by Letters Patent is:
1. A brake mechanism for aeroplanes comprising a pair of drag fins hingedly supported at their rear ends on opposite sides of the fuselage of an aeroplane, the fuselage being provided with cut out portions in the sides for the reception of the drag fins when the latter are in a closed position, means for holding the drag fins in a closed inoperative position, said means comprising a pair of keepers arranged on the inner sides of the respective drag fins adjacent the forward free ends thereof, a curved spring wire latch member, the free ends thereof adapted to extend into the keepers, said latch member adapted to be moved forwardly whereby the free ends thereof are disengaged from the keeper to permit the outward swinging movement of the drag fins to an operative position, and means for limiting the outward swinging movement of the drag fins.
2. A brake mechanism for aeroplanes comprising a pair of drag fins hingedly supported at their rear ends on opposite sides of the fuselage of an aeroplane, the fuselage being provided with cut out portions in the sides for the reception of the drag fins when the latter are in a closed position, means for holding the drag fins in a closed inoperative position, said means comprising a pair of keepers arranged on the inner sides of the respective drag fins adjacent the forward free ends thereof, a curved spring wire latch member, the free ends thereof adapted to extend into the keepers, said latch member adapted to be moved forwardly whereby the free ends thereof are disengaged from the keeper to permit the outward swinging movement of the drag fins to an operative position, and means for limiting the outward swinging movement of the drag fins.
